APPARATUS FOR AND A METHOD OF
DUPLICATINGJoseph H. Tathwell, Charlotte, N. C., assignor to
Ditto, Incorporated, Chicago, Ill., a corporation
of West Virginia

Application June 25, 1938, Serial No. 215,770

13 Claims. (Cl. 101—131)

The invention relates to apparatus for and a method of duplicating, and it has for its primary object the provision of improved apparatus for and an improved method of obtaining a copy on one sheet of data obtained from a plurality of other sheets.

In one form of the invention, the data to be duplicated is typewritten or written in positive with hectograph ink on a plurality of strips of paper, each of which strips, for example, may be the record of the weekly payroll data for a certain individual. Along one edge of each strip, data is typewritten or written giving the name of the individual and the amount the individual is to receive for the week. Other data, such as the number of hours or days of work for the week, may also be included. Each of these strips has a plurality of holes along one edge thereof so that the strips may be assembled in overlapping relationship upon a pegboard device with the matter to be duplicated appearing on the extending edge portions of the several strips, the pegs or pins of the board being much smaller in diameter than the holes in the strips. This differential size of the openings facilitates the task of distributing the strips upon the pegboard device in such manner that the data to be duplicated is left exposed. After the strips are mounted on the pegboard, they are aligned so as to be brought into proper position with respect to each other by pressure on the ends of the sheets along the assembly by means of an aligning member or bar, after which a clamp is employed to hold the strips in their aligned condition and the assembly is removed from the pegboard and applied face down to a gelatin pad so that the data to be duplicated appears in reverse upon the pad. A copy sheet may then be applied to the pad for duplicating in positive on the one sheet all of the exposed data appearing in hectograph ink on the several strips.

It is another object of my invention to improve apparatus of this type and the method of duplicating in sundry details as hereinafter set forth. The preferred means and methods by which I have accomplished my several objects are illustrated in the accompanying drawings, in which,

Fig. 1 is a perspective view of the preferred form of my improved structure for arranging a plurality of master sheets in assembled relation to each other for duplicating purposes.

Fig. 2 is an end view of the device of Fig. 1.

Fig. 3 is a top plan view of the device of Fig. 1 but with a plurality of master sheets loosely mounted in overlapping position thereon for ex-

posing a portion of a top face of each of said sheets.

Fig. 4 is a view similar to Fig. 3 but with the master sheets moved to their normal adjusted positions and with a gripping or clamping device mounted effectively in position on the adjusted sheets.

Fig. 5 is a vertical sectional view taken substantially at the line 5—5 of Fig. 4; and

Fig. 6 is a perspective view of the adjusted assembly of sheets with the clamping device thereon, such assembly being in inverted position with the exposed face portions of the several master sheets pressed into engagement with a gelatin duplicating member.

Referring now to the several figures of the drawings, in which corresponding parts are indicated by the same reference characters, 10 indicates a board or panel of any suitable type having a plurality of round pegs 11 secured in its top face in evenly spaced relation adjacent to one edge of the board, the pegs being in aligned position side by side. As is best shown in Figs. 2 and 5, the board 10 is provided with supporting members 12 of any suitable type at its corners on its bottom face for supporting the board evenly upon a table or other level surface.

In Fig. 3, there are shown a plurality of master sheets 13 each in the form of a comparatively narrow strip preferably formed of paper, having a plurality of openings 14 in their end portions of considerably greater diametrical size than that of the pegs 11. The openings 14 are arranged in evenly spaced relation to each other across the ends of the master strips 13, the spacing being such that the strips are capable of being mounted quickly and easily upon the pegs or pins 11, and being capable of having an edgewise shifting movement with respect to the board 10 when so mounted loosely upon the pegs.

In the arrangement as shown in Fig. 3, the openings 14 are circular in shape, so that the side portions of the openings adjacent to the edge of the sheet are obliquely disposed. As a result of this arrangement, when the sheets 13 are pressed in any manner toward the left in Fig. 3, the openings 14 are brought into centered position in one direction with respect to the pegs and the sheets or strips are aligned accurately in parallel position with respect to each other.

Means is provided on my improved board 10 for pressing the sheets 13 toward the left in Fig. 3, such means comprising a bar 15 which is hingedly mounted at its lower edge at 16 upon the edge of the board 10 (see Fig. 5), the ar-

angement being such that when the bar 18 is swung upwardly to its raised position as shown in Figs. 4 and 5, it is brought into forcible engagement with the end portions of the sheets or strips 13 so as to press such strips transversely of the board for effecting the desired alignment as above described.

For operating the aligning bar 18, I have provided a bracket 16a thereon having its outer end connected by a coiled spring 17 with a pin 18 carried by the board 16, the arrangement being such that the spring 17 passes centers in its movement from the position as shown in Fig. 2 to the position as shown in Fig. 5. As a result of this arrangement, the spring 17 serves to hold the alignment bar 18 yieldingly in its raised position as shown in Fig. 5 and serves alternatively to hold said alignment bar 18 in the position as shown in Figs. 1 and 2.

With a plurality of master strips 13 mounted loosely in position upon the pegs 11 on the board 16, as is clearly shown in Fig. 3, a portion of the top face of each of the strips is exposed to view; in the arrangement of the strips as shown in Fig. 25 3 the upper edge portion of each of said strips is so exposed. The master strips 13 are designed to have any desired data written in hectograph ink upon the top edge portion of each of the strips so that the copy ink entries are exposed 30 at the top face of the assembly as shown in Fig. 3. When the desired number of strips 13 has been placed in position upon the pegs 11, the alignment bar 18 is to be moved from the position as shown in Fig. 2 to the position as shown in Fig. 5, for bringing such bar into engagement with the end portions of the strips for moving them into adjusted parallel position as shown in Fig. 4, the spring 17 being of such strength as to bring the alignment bar up sharply to its raised position.

After the strips are brought into alignment as shown in Fig. 4, a gripping or clamping device 18 is to be applied to the free end portions of the strips as shown in said Fig. 4. In the arrangement shown, I have employed a clamping device comprising a plate 28, and a clamping bar 21 movably mounted with respect to the plate 28, such clamping bar 21 in the arrangement shown being provided with a pressure strip 22 preferably of rubber. The bar 21 in the arrangement shown is carried by an arm 23 which has a pivotal connection with the plate 28, a spring 24 being provided for normally holding the pressure strip 22 in engagement with the top face of the plate 28. In the arrangement shown, the plate 28 is provided with a downwardly extending flange 25 along one edge.

With an improved clamp 18 mounted upon the strips 13 as shown in Fig. 4, the operator is enabled to pick up the entire assembly of master strips 13 so as to free such assembly from the pegs 11, this operation being greatly expedited by the fact that the openings 14 are of enlarged size as compared with the size of the pegs 11. The grip of the clamping device 18 upon the sheets is such that the sheets are held strongly in their adjusted position with respect to each other so as to enable the operator to invert the entire assembly of sheets and grip 70 per device for pressing the top face portions of the strips 13 into engagement with a duplicating medium such as the gelatin bar 26 as shown in Fig. 6. After the perforated end portions of the assembled strips 13 are pressed into bonded relation with the gelatin member 26, the gripping

device 18 is removed and the gripped portions of the strips are pressed into bonded relation with the gelatin member.

After the master strips 13 have been left in position upon the gelatin member for the required period for insuring the proper bonding of the strips to the gelatin member, the master strips are to be removed from the gelatin member so as to leave the subject matter to be duplicated in reverse on the face of such gelatin member 26, as is well understood in this art. As the final step of the operation, copy sheets of any desired form are pressed against the gelatin member so as to take copies in positive therefrom. Such copy sheets may be of large size so as to copy the complete design from all of the master strips for the preparation of a record such as a payroll. On the other hand, the copy sheets may be in the form of checks or vouchers which are brought into impression relationship with only limited portions of the complete design so as to make a duplication of the data derived from only one of the master strips if so desired.

I have found in practise that my improved arrangement is very effective for the purposes for which it was evolved. I prefer therefore to employ the form of arrangement as shown in the drawings and as above described. It is to be understood however that my invention is not to be limited to the form of device as shown except so far as the claims may be so limited, it being understood that changes might well be made in the form of the device without departing from the spirit of my invention.

I claim:

1. A method of duplicating subject matter from a plurality of master strips, each having a plurality of openings therethrough at one edge portion, which method comprises arranging the strips adjustably in overlapping relationship on a series of pins so that a portion of each strip is exposed for duplicating purposes, aligning the strips by pressing them against said pins by pressure applied to the edges of said strips along one edge of the assembly of strips, clamping the strips together in adjusted position, and then applying the clamped assembly of strips face downwardly on a duplicating medium for transferring the subject matter in reverse from the several strips to said duplicating medium.

2. A method of duplicating subject matter from a plurality of master sheets each having a plurality of openings therethrough at one edge portion, which method comprises arranging the several sheets adjustably in overlapping relationship on a series of pins on a support so that a portion of the duplicating face of each sheet is exposed, adjusting the sheets accurately with respect to each other on said support for duplicating purposes by pressing them against said pins by manipulation of the sheets from one side only of the assembly of sheets, clamping the sheets together in adjusted position on the support, then removing the clamped sheets from the support and applying the assembly to a duplicating medium for transferring the subject matter in reverse from the several sheets to said duplicating medium, and then applying copy sheets to the duplicating medium for producing the composite subject matter in positive on said copy sheets.

3. A method of duplicating subject matter from a plurality of master sheets, which method comprises arranging the several sheets face upwardly in overlapping relationship so that said sheets are

free to have at least a slight swinging movement edgewise with respect to each other about axes arranged in substantial alignment with each other near one edge of the assembly of sheets, and so that a portion of each sheet is exposed at the top face of the assembly of sheets, then aligning the several sheets by pressure applied along the edge of the assembly of sheets adjacent to said line of axes, then clamping the sheets together in adjusted position, and then applying the clamped assembly of sheets face downwardly on a duplicating medium for transferring the subject matter from the several sheets in reverse to said duplicating medium.

4. A method of duplicating subject matter from a plurality of master sheets, which method comprises arranging the several sheets face upwardly in overlapping relationship to each other so that said sheets are free to have at least a slight edgewise movement with respect to each other and so that a portion of each sheet is exposed at the top face of the assembly of sheets, then moving the several sheets into parallelism with each other by pressure applied along one edge of the assembly of sheets, then clamping the sheets together in adjusted position, and then applying the clamped assembly of sheets face downwardly on a duplicating medium for transferring the subject matter from the several sheets in reverse to said duplicating medium.

5. A method of duplicating subject matter from a plurality of master strips, which method comprises arranging a plurality of comparatively narrow master strips of similar size and arrangement face upwardly in overlapping relationship to each other so that said strips are free to have an edgewise sliding movement with respect to each other and so that a transversely extending edge portion of each strip is exposed at the top face of the assembly of strips, then moving the several strips into parallel position with respect to each other by pressure applied evenly on the ends of the several strips at one edge of the assembly of strips, then clamping the strips together in their adjusted parallel positions, and then applying the clamped assembly of strips face downwardly on a duplicating medium for transferring the subject matter from the several strips in reverse to said duplicating medium.

6. An apparatus for duplicating from a plurality of master sheets having openings therethrough in spaced relation along corresponding edges, the combination of a board, pegs extending from the face of said board in aligned position side by side along one edge of the board in correspondingly spaced relation for enabling master sheets of the type named to be mounted adjustably thereon in overlapping relationship to each other, and means for applying pressure evenly along the board adapted by engagement with a plurality of master sheets on said pegs to move said master sheets into similarly aligned positions on said board.

7. An apparatus for duplicating from a plurality of master sheets having openings therethrough in spaced relation along corresponding edges, the combination of a board, pegs extending from the face of said board in aligned positions side by side along one edge of the board in correspondingly spaced relation to each other but of substantially smaller size than that of the openings in said master sheets whereby a plurality of said sheets mounted on the pegs in overlapping relationship to each other are adapted to be shifted edgewise with respect to each other on said pegs, and means for applying pressure evenly on cor-

responding edge portions of said master sheets serving to move said sheets into parallel position with respect to each other for duplicating purposes.

8. An apparatus for duplicating from a plurality of master sheets having openings therethrough in spaced relation along corresponding edges, the combination of a board, pegs extending from the face of said board in aligned positions side by side along one edge of the board in correspondingly spaced relation to each other but of substantially smaller size than that of the openings in said master sheets whereby a plurality of said sheets mounted on the pegs in overlapping relationship to each other are adapted to be shifted edgewise with respect to each other on said pegs, said openings in each of said master sheets having obliquely disposed side portions adjacent to the edge of the sheet so as to cooperate with said pegs for bringing the master sheets into parallelism with each other when the sheets are pressed transversely with respect to the board, and means movably connected with said board for applying pressure evenly on corresponding edge portions of said master sheets adjacent to said pegs for bringing said sheets into normal adjusted position with respect to each other for duplicating purposes.

9. An apparatus for duplicating from a plurality of comparatively narrow strips having openings therethrough in spaced relation to each other across corresponding ends of the strips and rounded at their outer face portions, the combination of a board, pegs extending from the face of said board in aligned positions side by side along one edge of the board in correspondingly spaced relation to each other and rounded on their outer face portions but of substantially smaller size than that of the openings in said master strips whereby a plurality of said strips mounted on said pegs in overlapping relationship to each other are adapted to be shifted edgewise with respect to each other when mounted loosely on said pegs and are adapted to be brought into parallelism with each other when the perforated end portions of the strips are pressed against said pegs, and means movably mounted on said board for applying pressure evenly on the perforated end portions of said strips adjacent to said pegs for bridging said strips into normal parallel adjusted position with respect to each other for duplicating purposes.

10. An apparatus for duplicating from a plurality of master sheets having openings therethrough in spaced relation along corresponding edges, the combination of a board, pegs extending from the face of said board in aligned position side by side along one edge of the board in correspondingly spaced relation for enabling master sheets of the type named to be mounted adjustably thereon in overlapping relationship to each other, a bar pivotally mounted on the edge of said board adjacent to said row of pegs in position to engage the edges of the master sheets mounted on said pegs, and yielding means for moving said bar forcibly into engagement with said sheets serving to move said sheets into similarly aligned positions on said board.

11. An apparatus for duplicating from a plurality of master sheets having openings therethrough in spaced relation along corresponding edges, the combination of a board, pegs extending from the face of said board in aligned position side by side along one edge of the board in correspondingly spaced relation for enabling

- master sheets of the type named to be mounted adjustably thereon in overlapping relationship to each other, a bar pivotally mounted on the edge of said board adjacent to said row of pegs in position to engage the edges of the master sheets mounted on said pegs, and a spring connected with said board and with said bar so as to move said bar forcibly into engagement with said sheets and serving thereby to move said sheets into similarly aligned positions on said board and adapted alternatively to hold said bar swung past centers away from the edge of the board.
12. An apparatus for duplicating from a plurality of master sheets having openings therethrough in spaced relation along corresponding edges, the combination of a board, pegs extending from the face of said board in aligned positions side by side along one edge of the board in correspondingly spaced relation to each other but of substantially smaller size than that of the openings in said master sheets whereby a plurality of said sheets mounted on the pegs in overlapping relationship to each other are adapted to be shifted edgewise with respect to each other on said pegs, said openings in each of said master sheets having obliquely disposed side portions adjacent to the edge of the sheet so as to cooperate with said pegs for bringing the master sheets into parallelism with each other when the sheets are pressed transversely with respect to the board, and a bar pivotally mounted on the edge of said board adjacent to said row of pegs in position to engage the edge portions of said master sheets for bringing said sheets into normal adjusted

position with respect to each other for duplicating purposes.

13. An apparatus for duplicating from a plurality of master sheets having openings therethrough in spaced relation along corresponding edges, the combination of a board, pegs extending from the face of said board in aligned positions side by side along one edge of the board in correspondingly spaced relation to each other but of substantially smaller size than that of the openings in said master sheets whereby a plurality of said sheets mounted on the pegs in overlapping relationship to each other are adapted to be shifted edgewise with respect to each other on said pegs, said openings in each of said master sheets having obliquely disposed side portions adjacent to the edge of the sheet so as to cooperate with said pegs for bringing the master sheets into parallelism with each other when the sheets are pressed transversely with respect to the board, a bar pivotally mounted on the edge of said board adjacent to said row of pegs adapted by an operative stroke to engage the edge portions of said master sheets for bringing said sheets into normal adjusted position with respect to each other for duplicating purposes, and a spring connected with said board and with said bar and arranged to pass centers adapted in one position to cause said bar to press forcibly against corresponding edge portions of said sheets for bringing said sheets into parallelism with each other and adapted in a changed position to hold said bar swung away from the edge of the board.

JOSEPH H. TATHWELL.
